(80) **Hague Agreement Data**

Int. Filing Date: **Dec. 4, 2019**

Primary Examiner — Khawaja Anwar

Int. Reg. No.: **DM/205942**

CLAIM

Int. Reg. Date: **Dec. 4, 2019**

The ornamental design for a computer printer, as shown and described.

Int. Reg. Pub. Date: **Jun. 5, 2020**

DESCRIPTION(30) **Foreign Application Priority Data**

1.-2. Computer printer

Jun. 7, 2019 (JP) 2019-012587
 Jun. 7, 2019 (JP) 2019-012588
